DESIGN FOR A TOY WHEELBARROW

Howard D. Allen, Los Angeles, Calif.

Application May 25, 1945, Serial No. 119,736

Term of patent 14 years

(Cl. D34—15)

To all whom it may concern:

Be it known that I, Howard D. Allen, a citizen of the United States, residing at 4620 West Avenue 41, Los Angeles, in the county of Los Angeles and State of California, have invented a new, original, and ornamental Design for a Toy Wheelbarrow, of which the following is a specification, reference being had to the accompanying drawing, forming part thereof.

Fig. 1 is a side elevational view of a toy wheelbarrow showing my new design; and

Fig. 2 is a front elevational view thereof.

I claim:

The ornamental design for a toy wheelbarrow, as shown.

HOWARD D. ALLEN.
